UNITED STATES PATENT OFFICE.

AUGUST NIKANDER, OF DETROIT, MICHIGAN, ASSIGNOR OF ONE-HALF TO SAMUEL E. ROTHSTEIN, OF DETROIT, MICHIGAN.

SCRIBING TOOL.

Application filed October 26, 1922. Serial No. 597,004.

To all whom it may concern:

Be it known that I, AUGUST NIKANDER, a citizen of the Republic of Finland, residing at Detroit, in the county of Wayne and State of Michigan, have invented new and useful Improvements in Scribing Tools, of which the following is a specification.

This invention relates to tools used in the metal and wood-working trades for scratch-
10 ing or scoring lines on the material to accurately locate the places where the same is to be cut, and the invention has for its object to provide a very simple and efficient tool of this kind, the same consisting of a
15 novel combination and arrangement of parts to be hereinafter described and claimed.

In order that the invention may be better understood, reference is had to the accompanying drawing, wherein—

20 Figure 1 is a plan view of the tool;

Figs. 2 and 3 are side elevations illustrating two different ways of using the tool, and

Fig. 4 is a side elevation of a modification.

Referring specifically to the drawing, and
25 more particularly to Figs. 1 to 3, the reference numeral 10 denotes a scale blade having at one of its ends an upstanding flange 11 which may be formed by a right-angled bend in the blade. The scale graduations
30 are on that side of the blade from which the flange projects. A short distance from the flange 11, and on the same side of the blade 10 as said flange, the blade carries a post 12 having a transverse aperture in which is
35 slidably mounted a graduated scribe rod 13. A set screw 14, threaded into the post to engage the scribe rod is employed for holding the latter in adjusted position.

The scribe rod 13 projects from opposite
40 sides of the post 12 so that one end may lie above the graduated side of the blade 10, whereas its other end passes loosely through an aperture in the flange 11. Each end of the scribe rod has a scribing point, the same being denoted by the reference numerals 15 and 16, respectively. Both scribing points may be lateral bends at the ends of the rod, said bends having sharpened or pointed extremities.

45 The scribing point 15 is used principally in automobile body and other sheet metal work where the sheet metal is to project a certain distance from the edge of the wood so that it may be bent over the same. In
50 using the tool for this work, the scribe rod

13 is slid until the point 15 is opposite the graduation on the blade 10 which denotes the desired distance the metal is to project from the edge of the wood. The rod is locked in adjusted position by the set screw 60 14. The point 15 being now located inwardly of the end of the blade, the tool is placed so that the projecting piece of metal comes between the point and the opposite side of the blade 10, and the latter is then 65 advanced until the aforementioned end thereof comes in contact with the edge of the wood, as shown in Fig. 2. It will be understood that the scribe point is spaced from the scale blade a sufficient distance to permit 70 the sheet metal to be marked to come therebetween. Now, with the edge of the wood guiding the blade 10, the latter is drawn along said edge so that the scribe point 15 may scratch a line on the metal. A slight 75 pressure on the rod 13 in a direction to bring the scribe point in contact with the metal to be marked suffices to scratch the line on the same.

As shown in Fig. 3, the scribe point 16 80 may be used for scratching a line a certain distance from the edge of a piece of wood, the rod 13 being set to leave the point projecting this distance from the flange 11, and the latter being placed against the edge of 85 the work to guide the tool. The scale on the rod 13 is used for this setting of the scribe point 16.

Fig. 4 shows a slight modification. Here, 90 instead of the scribe point 16, a rotatable scribe wheel 17 is provided.

I claim:

1. A scribing tool comprising a scale blade having one side graduated, a post on the graduated side thereof, and a longitudinally 95 adjustable rod carried by the post and extending parallel to the blade, said rod having a scribe point positioned opposite and spaced from the graduated side of the scale blade. 100

2. A scribing tool comprising a scale blade having one side graduated, a post on the graduated side thereof, and a longitudinally adjustable rod carried by the post and extending parallel to the blade, said rod having a lateral end bend in the direction of the graduated side of the scale blade, with its extremity pointed and spaced from said side. 105

3. A scribing tool comprising a scale blade 110

having one side graduated and having an apertured lateral flange at one end, a post on the graduated side of said blade, and a longitudinally adjustable rod carried by the post parallel to the blade, said rod having scribes at its ends, and one end of the rod passing loosely through the aperture of the aforesaid flange.

4. A scribing tool comprising a scale blade
10 having one side graduated and having an

apertured lateral flange at one end, a post on the graduated side of said blade, and a longitudinally adjustable and graduated rod carried by the post parallel to the blade, said rod having scribes at its ends, and one 15 end of the rod passing loosely through the aperture of the aforesaid flange.

In testimony whereof I affix my signature.

AUGUST NIKANDER.
